UNITED STATES PATENT OFFICE

2,122,002

INTERNAL COMBUSTION ENGINE

Joseph W. Catron, Bigelow, Mo.

Application January 25, 1937, Serial No. 122,265

2 Claims. (Cl. 123—56)

This invention relates to internal combustion engines and more particularly to internal combustion engines of the two cycle types; an object of the invention being to provide a compact form of explosive engine adapted to produce great power with a high degree of efficiency.

The invention together with its objects and advantages will be best understood from a study of the following description taken in connection with the accompanying drawings wherein:

Figure 1 is a side elevational view of the engine.

Figure 2 is a longitudinal sectional view through the engine with certain parts shown in elevation taken on the line 2—2 of Fig. 3 looking in the direction indicated by the arrows.

Figure 3 is a longitudinal sectional view through the engine taken on the line 3—3 of Fig. 1, looking in the direction indicated by the arrows.

Figure 4 is a transverse sectional view through the engine.

Figure 5 is a side elevational view of the power piston.

Figure 6 is an end elevational view thereof.

Referring to the drawings by reference numerals it will be seen that the internal combustion engine which is of the two cycle type comprises a crankcase 5 of suitable shape and dimension provided at its respective opposite ends with flanges 6 through the medium of which, together with flanges 7 provided on one end of cylinders 8, and bolts 9, cylinders 8 are secured to the crankcase 5 at relatively opposite ends of the latter.

Interposed between each flange 6 and the flange 7 of a cylinder 8 is a gasket 10.

A power piston 11 has an intermediate portion suitably shaped to work within the crankcase 5 and respective opposite end portions 12 that have a working fit within the cylinders 8.

At opposite sides thereof the crankcase 5 is provided with bearings 13 in which are journaled crankshaft sections 14. At the inner ends thereof the crankshaft sections 14 are provided with crank arms 15 which at one end are enlarged as at 16 to increase the weight of the arms at said end.

The arms 15 are connected by a pin 17 through the medium of which and a bearing 18 the connecting rod 19 is connected with the crank arm.

To accommodate the crankshaft sections 14 piston 11 is provided at diametrically opposite sides thereof with elongated slots 20.

Also the piston 11 in one of the ends 12 thereof is provided with a wrist pin 21 to which is suitably connected the connecting rod 19 for

transmitting power from the cylinder to the crankshaft.

The cylinders 8 are provided with exhausts 22 that extend laterally therefrom and with intake valve cylinders 23 that extend from the heads 5 of said cylinders.

Integral with or otherwise connected to the ends 12 of the piston 11 are valve rods or core members 24 that have a working fit in the valve cylinders 23 and are provided at their respective 10 outer or free ends with fuel passages 25.

At their free ends the valve cylinders 23 are connected as at 26 with conduits 27 that lead from a suitable source of fuel supply, preferably a super-charger (not shown).

Also in the heads thereof the cylinders 8 are provided with spark plug holes in which are threaded spark plugs 28.

The manner in which the engine operates is thought to be obvious to those skilled in the art 20 but may be briefly explained as follows:

As the piston 11 moves, for example, from the position shown in Figure 2 to the right fuel from the super-charger passes through the valve port 25 at the right of Figure 2 and into the cylinder 25 8 at the right of Figure 2 when the piston 11 has moved to the extreme right. Obviously as piston 11 moves to the right, for example, valve arm 24 on the right hand end of the piston 11 moves into its cylinder 23 thus closing the passage 25 30 of the valve rod 24, just mentioned, and the fuel within the cylinder 8 at the right of Figure 2 is compressed and exploded as the piston 11 completes this movement to the right. Also in this connection it will be understood that as the 35 piston 11 moves to the right the products of combustion in the cylinder 8 at the right of Figure 2 will be forced therefrom through the exhaust 22 provided for the last mentioned cylinder.

Obviously the force of the explosive charge in 40 the cylinder at the right of Figure 2 will cause the piston 11 to move towards the left and as this cycle of operation is repeated drive is transmitted to the crankshaft and to the work connected with the crankshaft for driving the latter.

It is thought that a clear understanding of the construction, utility and advantages of the invention will be had without a more detailed description it being understood of course that suitable ignition means with which the spark plugs 28 are connected, and other necessary instrumentalities will be employed in conjunction with the engine embodying the features of the present invention.

Having thus described the invention, what is claimed as new is:—

1. In an internal combustion engine, a crank case, power cylinders secured to the crank case at the respective opposite ends of the latter, a piston having relatively opposite end portions working in said cylinders, a crank shaft journalled in the crank case and having shaft sections extending through slots in diametrically opposite sides of said piston, a crank connecting the crank shaft sections internally of the piston, a connecting rod connecting said crank with the piston, said cylinders being provided with exhaust ports, and means to deliver an explosive charge to said cylinders alternately comprising a pair of valve cylinders extending axially from opposite ends of the first mentioned cylinders, respectively, and a pair of solid valve rods, slidably fitting into said valve cylinders and extending axially from opposite ends of the piston, respectively, each rod being provided in the outer end thereof with an arcuate fuel delivery port opening at the ends thereof onto the outer end and peripheral face of the rod.

2. In an internal combustion engine, a crank case, power cylinders secured to the crank case at the respective opposite ends of the latter, a piston having relatively opposite end portions working in said cylinders, a crank shaft journalled in the crank case and having its opposite ends extending through slots in diametrically opposite sides of the piston, and a central crank portion located in said piston, a connecting rod connecting said crank portion with said piston, and means to deliver an explosive charge to said cylinders alternately, comprising a pair of valve cylinders extending axially from opposite ends of the first mentioned cylinders, respectively, and a pair of solid valve rods slidably fitting into said valve cylinders and extending axially from opposite ends of the piston, each rod being provided in the outer end thereof with a fuel delivery port opening at the ends thereof onto the outer end and peripheral face of the rod. 20

JOSEPH W. CATRON.
